CLAIM

The ornamental design for a safety cap for a medical injector, as shown and described.

DESCRIPTION

FIG. 1 is a top perspective view of a safety cap for a medical injector showing our new design;

FIG. 2 is a bottom perspective view thereof;

FIG. 3 is a front elevation view thereof;

FIG. 4 is a top plan view thereof;

FIG. 5 is a left side elevation view thereof;

FIG. 6 is a right side elevation view thereof;

FIG. 7 is a rear elevation view thereof;

FIG. 8 is a bottom plan view thereof;

FIG. 9 is a top perspective view of the safety cap for a medical injector of FIG. 1 mounted to a medical injector;

FIG. 10 is a bottom perspective view thereof;

FIG. 11 is a rear elevation view thereof;

FIG. 12 is a top plan view thereof;

FIG. 13 is a left side elevation view thereof;

FIG. 14 is a right side elevation view thereof;

FIG. 15 is a front elevation view thereof; and,

FIG. 16 is a bottom plan view thereof.

The dash-dash broken lines depicting a medical injector, illustrate environmental subject matter that forms no part of the claimed design.

1 Claim, 8 Drawing Sheets
